United States Patent Office.

CHARLES DE HASS, OF WASHINGTON CITY, DISTRICT OF COLUMBIA.

Letters Patent No. 77,177, dated April 28, 1868.

IMPROVED MODE OF ROOFING BUILDINGS.

The Schedule referred to in these Letters Patent and making part of the same.

TO ALL WHOM IT MAY CONCERN:

Be it known that I, CHARLES DE HASS, of the city of Washington, and District of Columbia, have invented a new Mode of Roofing Buildings, termed the "Concrete Roofing," and do hereby declare that the following is a full and exact description thereof, reference being had to the accompanying draught of the same.

To enable others skilled in the art to make and use my invention in roofing buildings, I proceed to describe the preparation of the roof of the building, and the ingredients used in compounding the concrete for the roofing-material, and the application of the same to the roof of the building.

The roof of the building is arranged in the ordinary manner, and sheeted with inch plank, similar to that for shingles. On this sheeting, rolled iron rails, of the T-form, half an inch high, are inversely nailed, running from top to bottom of the roof, two and a half feet asunder. These rails are designed for the double purpose of holding the concrete in its position, and to enable the operator to give a uniform thickness to the roof.

The concrete roofing-material is composed of three parts of clear, sharp sand, and one part each of hydraulic cement and lime, slightly moistened with water, heated, and thoroughly mixed.

After the preparation of the concrete as indicated, it is to be spread by the operator, in the ordinary manner of spreading mortar, between the two first set of rails, filling the entire space between and to the top of the rails, and at the same instant compactly rolling the concrete with a heavy iron roller. This operation is to be performed speedily on the remaining sections, as the concrete hardens very rapidly.

A thin finishing-coat is now applied, composed of equal parts of clear, fine sand and asphaltum, for the purpose of making the roof still more impervious to water.

What I claim as my invention, and desire to secure by Letters Patent, is—
A roof, constructed as herein described.
